UNITED STATES PATENT OFFICE.

ALBERT GLOOR, OF CHICAGO, ILLINOIS.

WRENCH.

1,178,007.

Specification of Letters Patent.

Patented Apr. 4, 1916.

Application filed January 31, 1916. Serial No. 75,274.

To all whom it may concern:

Be it known that I, ALBERT GLOOR, a citizen of the United States, and resident of Chicago, in the county of Cook and State of Illinois, have invented certain new and useful Improvements in Wrenches, of which the following is a specification.

My invention relates to wrenches. Its general object is to provide a wrench suitable for holding articles of various general shapes where the effective and satisfactory holding of such variously shaped articles calls for variously shaped or surfaced jaws, for instance a serrated or toothed gripping surface for round objects such as pipes, and a plane or angular surface for nuts and the like.

More specific objects are to provide a wrench of the character mentioned which is simple of construction, strong and durable, of light weight, of few parts, which may be produced at relatively low cost, and which is easy, convenient and highly effective in operation.

Other objects and advantages will appear hereinafter.

In the accompanying drawings, which form a part of this specification, I have illustrated a preferred embodiment of these improvements as incorporated in a well known general type of pipe wrench, the specific adaptation of the jaws illustrated being, broadly speaking, for round and plane-surfaced objects, such as pipes and nuts.

In these drawings, Figures 1 and 2 are face views respectively of the wrench with its auxiliary jaw shown respectively on opposite sides of the main jaw opening; Fig. 3 is a transverse vertical sectional view of the wrench on the line 3-3 of Fig. 2; and Fig. 4 is a horizontal section through the movable jaw and auxiliary jaw on the line 4-4 of Fig. 2. The scale of Figs. 3 and 4 is somewhat enlarged.

Referring to the drawings, the main shank 10 carries a handle 11 at one end and is formed to provide the relatively fixed jaw 12 at the other end thereof. The movable jaw 13 is integral with the threaded stem 14, passing loosely through an opening 15 in

the yoke-like element or keeper 16, which keeper is pivotally mounted, as at 17, upon the shank 10 whereby it may rock to a limited degree thereon. A thumb nut 18 loosely confined in the transverse opening 19 of the keeper or yoke is threaded upon the stem 14, the rotation of the nut moving the jaw 13 adjustably away from and toward the fixed jaw 12 in order to hold objects of various sizes.

Between the jaws 12 and 13 I provide an auxiliary jaw 20 which is operative intermediate the other two jaws and movable relative to each thereof. In Fig. 1 it is shown as contacting the jaw 12 while in Fig. 2 it is in contact with the jaw 13. A space for receiving objects to be held is thus provided between the auxiliary jaw and each of the other two jaws in turn. In the ordinary pipe wrench of the general character illustrated both the jaws, as 12 and 13, are serrated or provided with teeth whereby the desired grip upon pipes or rods may be had. In my improved wrench I prefer to serrate the gripping or holding surface of only one of these jaws, preferably the relatively movable jaw 13, as at 21, leaving the jaw 12 with a plane and relatively smooth surface, as 22. The auxiliary or intermediate jaw 20 is preferably also serrated upon that face thereof, as 23, which is toward the serrated surface on the other jaw, while the face 24 thereof is preferably plane and relatively smooth, where, as in the instance illustrated, the tool is what may be termed a combined pipe and nut wrench. The jaws may be formed or surfaced otherwise, of course, according to preference or for particular special purposes. It is clear that when the auxiliary jaw 20 is moved so as to lie against or in pressure-receiving relation to the jaw 12 an opening, as 25, may be had between the jaws 20 and 13 adapted to hold pipes and similar round objects, while, when the auxiliary jaw 20 is moved so as to contact or be in pressure-receiving relation to the jaw 13 an opening, as 26, is provided adapted to hold nuts and other similar or flat objects after the manner of any well known wrench, for instance the ordinary monkey wrench.

Owing to the adjustability of the jaw 13 the openings 25 and 26 may of course vary from nothing at all up to that provided by the full extension of the jaw 13.

5 In order to secure the auxiliary jaw 20 in its desired position with suitable strength, adjustability for all degrees of extension of the movable jaw and in the preferred manner whereby the auxiliary-jaw-supporting-
10 and-retaining means are within the side planes of the tool, and also whereby certain additional advantages later herein mentioned may conveniently be had, I provide a stem or extension 28 from the intermediate
15 jaw 20, preferably integral therewith, and preferably held by one or both of the relatively fixed parts 10 and 14. According to the illustrations I am considering the stem 28 as held by the shank 10. In the preferred
20 construction the shank 10 and the intermediate jaw support 28 are dove-tailed together, whereby the support 28 may slide relative to the shank 10 and in the direction of the adjustments of the movable jaw 13,
25 the tenon 29 being shown as upon the stem or support 28 while the mortise groove 30 is cut in the shank 10.

It is preferable during the use of the tool that the intermediate jaw 20 be held in its
30 desired relative position with respect to one or the other of the jaws 12 and 13. The means for this purpose shown comprise a swinging catch mounted on the intermediate jaw 20 and consisting of a pivotal
35 through-pin 31 having an arm 32 at each end thereof, the ends of these arms 32 being turned toward each other as at 33, the jaws 12 and 13 having on each side thereof
40 grooves 34 cut on an arc having the radius of the swinging arms 32, the ends 33 of the arms being adapted to enter the grooves 34 on the jaws 12 or 13 and thus releasably hold the intermediate jaw against one or the other as desired.

45 As mentioned, the keeper 16 is pivotally mounted, giving rise to a certain relative tilting movement of the jaw 13 desirable in a pipe wrench, the action causing the movable jaw 13 to bind upon the object being held when an object-holding or turning movement is applied upon the handle, the object being automatically released when the handle is moved in the opposite direction for the next grip. Such action, however, is
50 not desirable in a wrench for nuts and the like as it permits the opposing jaws to come out of their desired substantially parallel arrangement, thus causing slippage as well as incident injury to the corners of the nut.
55 To overcome this tilting action in one use of the device while preserving it for practical purposes in the other I provide a stop, as 36, upon the intermediate jaw-support 28 so positioned and of such proportions that

when the intermediate jaw 20 is against the 65 jaw 13, as in Fig. 2, the stop 36 is substantially in contact with the adjusting stem 14, thus effectively preventing the swinging or tilting of the jaw 13 on the pivot 17 in an upward direction when viewed as in Fig. 2, 70 the stop 36 being also so formed and positioned that when the intermediate jaw 20 is moved against the jaw 12, as in Fig. 1, the stop 26 is out of such holding relation and the movable jaw 13 is free to tilt relative to 75 the jaw 12 as desired.

Heretofore in such general type of pipe wrenches a pair of springs has been ordinarily employed to maintain the movable jaw, as 13, with its holding face, as 21, substantially parallel with the opposing face, as 22, of the jaw 12, the tilting or rocking motion hereinabove referred to being had against the resistance of such springs. One of such springs, substantially as heretofore used, is the spring 38 rigid with the shank 10 and pressing against an inner wall of the extension 16^a of the keeper 16. The other spring heretofore used has been substantially of the character of the leaf spring 39, 90 pressing against the transverse wall 40 between the openings 15 and 41 of the keeper 16. Heretofore the spring, as 39, has been secured upon the main shank, as 10. In my present improvements this spring 39 is secured upon the sliding stem 28, the front end of the spring 39 being turned somewhat toward the slide 28 so that when the jaw 20 is moved in a direction away from the handle 11 the spring 39 will be sure to pass 100 under the nut 18. When the parts are in the relative position of Fig. 1 the springs 38 and 39 coöperate to maintain the working faces of the jaws 12 and 13 substantially parallel. 105

In practice a workman, for instance in plumbing operations, is constantly in need of a wrench for pipes and a wrench for nuts and the like, and ordinarily two wrenches for this purpose are required. In view of 110 the advantages of my present invention only one wrench is necessary, a very simple movement of the fingers releasing the intermediate jaw and transferring same to the opposite side of the jaw opening where it is as easily secured, and thus within the space of a few seconds the workman can provide himself with an efficient pipe wrench or a nut wrench without leaving his work to look for another tool. 115

The improved device can be made and sold at a relatively small increase of cost over the ordinary wrench to which it may be adapted. Its use also lessens the bulk and weight of tool equipment to be carried about. 120

All of the wrench parts will readily be formed and assembled according to practices well understood in the mechanic arts. 125

While I have illustrated these improvements in combination with a certain well known type of wrench, in which type it is peculiarly advantageous, it will readily be understood that the same may be applied to other forms of wrenches, and also that various changes and modifications may be made in the specific details and arrangements of parts herein shown and described, all within the true spirit of the invention and improvements herein set forth. Reference should, therefore, be had to the appended claims to determine the scope of this advance in the art, and I contemplate all such changes and modifications from what is illustrated herein as are included in these claims.

I claim:

1. In a wrench, the combination of a shank having a relatively fixed jaw, a relatively movable jaw adjustably mounted on said shank to move from and toward said relatively fixed jaw, an auxiliary jaw intermediate said other two jaws, said auxiliary jaw having a stem slidably mounted in said shank whereby said auxiliary jaw may be moved to provide a space between it and each of said two jaws alternately for the reception of objects to be held, the object-holding surfaces on said intermediate jaw and on said other two jaws respectively being so formed that objects of one general shape may be held between said intermediate jaw and said relatively fixed jaw and objects of another general shape may be held between said intermediate jaw and said relatively movable jaw, and means for holding said intermediate jaw in operative position.

2. A wrench comprising in combination a relatively fixed shank having a jaw, a yoke member mounted on said shank, a relatively movable jaw having a screw-threaded stem extending loosely through an opening in said yoke member and substantially parallel with said shank, an adjusting nut-like element on said threaded stem and loosely confined in said yoke member, an auxiliary jaw between said other two jaws and having a gripping surface for objects of one general shape toward one of said jaws and having a gripping surface for objects of another general shape toward the other of said jaws, said auxiliary jaw having a stem slidably mounted in said shank whereby it may be moved against each of said other jaws alternately, and means for holding said auxiliary jaw releasably against one of said other jaws.

3. A wrench comprising in combination a relatively fixed shank having a jaw, a yoke member mounted on said shank, a relatively movable jaw having a screw-threaded stem extending loosely through an opening in said yoke member and substantially parallel with said shank, an adjusting nut-like

element on said threaded stem and loosely confined in said yoke member, an auxiliary jaw between said other two jaws and mounted for movement into pressure-receiving contact with each thereof alternately, said auxiliary jaw having a stem extending substantially parallel with said shank and slidably mounted therein by a dove-tail connection, said auxiliary jaw having two object-holding surfaces, the object-holding surfaces on said auxiliary jaw and on said other two jaws respectively being so formed that objects of one predetermined general shape may be held between said auxiliary jaw and said relatively fixed jaw and objects of another predetermined general shape may be held between said auxiliary jaw and said relatively movable jaw.

4. A wrench comprising in combination a relatively fixed shank having a jaw, a yoke member mounted to rock on said shank, a relatively movable jaw having a screw-threaded stem extending loosely through an opening in said yoke member and extending substantially parallel with said shank, a thumb nut on said threaded stem and loosely confined by said yoke member, an auxiliary jaw between said other two jaws and mounted for movement into pressure-receiving contact with each thereof alternately, said auxiliary jaw having two object-holding surfaces, the object-holding surfaces on said auxiliary jaw and on said other two jaws respectively being so formed that objects of one predetermined general shape may be held between said auxiliary jaw and said relatively fixed jaw and objects of another predetermined general shape may be held between said auxiliary jaw and said relatively movable jaw, said auxiliary jaw having a stem slidably mounted on said shank, said last mentioned stem carrying a stop adapted to contact said threaded stem whereby said movable jaw is substantially held against a rocking movement in one direction when said auxiliary jaw is in operative position against said movable jaw, the arrangement being such that said stop comes out of holding engagement with said threaded stem when said intermediate jaw is in operative position against said relatively fixed jaw.

5. In a wrench having a relatively fixed jaw and a relatively movable jaw adjustably mounted whereby the space between said jaws may be varied and mounted whereby said movable jaw may rock relative to said relatively fixed jaw, the combination therewith of an auxiliary jaw between said other two jaws and mounted whereby it may be moved against each of said two jaws alternately, the two holding faces of said auxiliary jaw and the holding faces respectively of said other two jaws being so formed that when said intermediate jaw is against said

relatively fixed jaw an object of one predetermined general shape may be held between said auxiliary jaw and said movable jaw and when said auxiliary jaw is against said movable jaw an object of another predetermined general shape may be held between said auxiliary jaw and said relatively fixed jaw, and means under the control of said auxiliary jaw for maintaining said movable

jaw substantially against rocking movement 10 in one direction relative to said relatively fixed jaw when said intermediate jaw is substantially against one of said other two jaws.

ALBERT GLOOR.
